UNITED STATES PATENT OFFICE.

CHARLES F. RANDALL, JOSEPH T. CLARK, AND JAMES T. SMITH, OF SPRINGFIELD, MASSACHUSETTS, ASSIGNEES TO SUPERIOR DAMPER COMPANY, OF SPRINGFIELD, MASSACHUSETTS, A COPARTNERSHIP.

DAMPER.

1,408,223.

Specification of Letters Patent. Patented Feb. 28, 1922.

Application filed May 16, 1921. Serial No. 470,138.

To all whom it may concern:

Be it known that we, CHARLES F. RANDALL, JOSEPH T. CLARK, and JAMES T. SMITH, citizens of the United States of America, residing at Springfield, in the county of Hampden and Commonwealth of Massachusetts, have invented certain new and useful Improvements in Dampers, of which the following is a specification.

10 This invention relates to improvements in dampers or draft regulators for stoves, furnaces and like heat producing apparatus.

An object of the invention is to provide a damper structure that will permit the products of combustion to readily pass up the chimney or stove pipe, and at the same time will prevent the escape of, or hold back, the combustible gases which are liberated during the burning or consumption of the fuel.

15 These gases, as is well known, contain elements of combustion which are capable of increasing the thermal efficiency of the heating apparatus if ignited before passing or escaping up the chimney. In other words,

20 these unconsumed gases include elements which, when combined with the proper quantity of air, will ignite, thus producing a flame, which thereby increases the thermal efficiency of the heating apparatus. In

25 order to bring about this increased efficiency the present improvement provides means for temporarily retaining or holding these gases in the combustion chamber until they are thoroughly consumed before permitting

30 them to escape up the stove pipe.

The present invention broadly considered comprises a damper construction in which a centrally disposed plate is provided and plates located on the opposite sides of the same to serve as a check or baffle to prevent the escape of the combustible gases before they are thoroughly consumed. These oppositely disposed plates also prevent any back or down draft from the chimney from 45 counteracting the normal or upward flow of the products of combustion.

These and other objects of the invention will appear in the body of the specification and will be pointed out in the claims.

50 Referring to the drawing:

Fig. 1 is a plan view, showing the stove pipe in section, the damper part, and the means for moving the same.

Fig. 2 is a sectional view on the line 2—2

of Fig. 1, showing the means for attaching 55 the spindle or shaft to the damper.

Fig. 3 is a sectional view of Fig. 1 taken on a plane through the axis of the shaft.

Fig. 4 is a detail sectional view on the line 4—4 of Fig. 1.

Fig. 5 is a view looking from the left hand end of Fig. 1 showing the hand wheel means for opening the damper.

Fig. 6 is a view on the line 6—6 of Fig. 1.

Referring to the drawing in detail: 1 designates the usual stove pipe, 2 the centrally located plate of the damper having the usual opening 3 therethrough. 4 and 5 are the baffle plates which are located on the opposite sides of the plate 2. These plates, as 70 shown, are made solid or free from any opening of any kind. They are secured to the plate 2 by means of the integral post members 6, 7, 8, and 9 which are indicated on one side of the plate 4 in plan view in Fig. 1 and in elevational view in Fig. 3. These posts are understood to be cast integral with the plates 2, 4, and 5, and are of such length as to provide a suitable space between the plates, as indicated at 10 and 80 11. The diameters of the plates 4 and 5 are smaller than that of the intermediate plate 2.

For the purpose of rotatably supporting the damper, spaced pivot or shaft pins 12 and 13 are employed, which pins are formed 85 with laterally projecting or wing parts 14 and 15 which pass through the grooves or channels 16 and 17 (see Figs. 2 and 4) against the tension of the springs 18 and 19.

When the wing parts 14 and 15 pass out of 90 the grooves or channels 16 and 17 the operator turns these pins through an arc of 90° permitting the wing parts to seat in the recesses 20 and 21, as shown in Fig. 4. The expansive force of the springs 18 and 19 will 95 serve to retain the pins in this position, whereby when the pin or shaft 12 is rotated by the hand wheel 22 the damper as a whole will be turned. As shown in Fig. 2 the plate 2 is formed with an enlarged portion 100 2' in which the grooves or channels 16 and 17 are placed and in which the shaft 12 is located. 2' designates an opening to receive the end of the shaft 12. 23 is a recessed knob or stop member which is pinned to the shaft 13, as indicated at 24. The spring 19 is seated in the recess 23'. 25 designates a plate which is secured to the stove pipe 1

by means of the bolts 26. This plate is formed with sockets 27 to receive the pins 28 of the spring actuated and damper locking plate 29. This plate is held in locking 5 position by means of the spring 18 and has a rib and groove connection with the shaft 12, as indicated at 12'. 30 designates a cord or wire rope for operating or drawing the plate 29 outward, as indicated in dotted lines 10 in Fig. 1 in a tilted position. This cord passes through an opening 31 in the damper operating wheel 22 and over a pulley 33 and then downward at 30' within reach of the operator. For turning the damper after 15 the locking pins 28 are withdrawn, a cord 35 is attached to the hand wheel 22 which passes over a pulley 36 and downward within reach of the operator. When the damper has been turned through the angle desired, the operator releases his hold on the cord 30 permitting the spring 18 to return 20 the plate 29 and pin 28 to the proper recess 27.

The direction of the burnt gases and products of combustion is indicated by the arrows 37, 38, 39, and 40 which show that the drafts or currents of burned gases from the fuel are first deflected around the baffle plate 4, then through the space 10, next through 25 the opening 3 and then outward through the space 11 to the stove pipe.

In this way the unconsumed gases in the fire box or over the burning fuel are held back for a sufficient length of time to permit 30 their full consumption before passing up the stove pipe.

It is, of course, obvious that proper adjustment of the angular position of the damper is necessary in order to have correct draft, 35 and at the same time perfect combustion.

It is also obvious that by the use of the baffle plate 5 any down draft is prevented from reaching the fire box and destroying the draft.

40 By the use of the two baffle plates 4 and 5 the opening 3 in the usual damper or center plate 2 is shielded or prevented from affording a free and unobstructed path for the unconsumed gases, which, as stated, are drawn 45 or forced upward through the stove pipe and chimney without being properly consumed.

It will therefore be seen that we have provided a damper construction that is formed or cast in one piece, which is inexpensive, but also one that can be readily adjusted in any desired position.

What we claim is:

1. In a damper construction, the combination with a stove pipe, a damper located

therein, shafts for pivotally supporting the 60 damper in the stove pipe, means for retaining the damper in different angular positions of adjustment and for permitting its adjustment into these positions, said means comprising a plate connected to one of the 65 shafts and mounted for movement thereon, a spring for moving the plate towards the stove pipe, a plate on the stove pipe, interengaging devices between the plates, whereby when the plate on the shaft is moved 70 against the spring away from the stove pipe the damper may be adjusted, and when the spring moves it towards the stove pipe the damper is retained in its adjusted position.

2. In a damper construction the combination with a stove pipe, a damper located therein, rods for pivotally supporting the damper in the stove pipe, means for retaining the damper in different angular positions of adjustment, as described, said means including a plate connected to the stove pipe and formed with sockets, a second plate connected to one of the rods and having a projection for entering the sockets of the first plate and means for disengaging the projections.

3. A damper construction comprising in combination with a stove pipe, a damper therein, shaft devices for pivotally supporting the damper in the stove pipe, a plate secured to the pipe having sockets therein, a second plate having a pin which is secured to the shaft devices, and normally engaging the socketed plate, a hand wheel on the device an operating device connected to the 95 second plate to disengage the same from the socketed plate for simultaneously turning the wheel and damper when the second plate is disengaged from the first plate.

4. In a damper construction, the combination with a stove pipe, of a damper therein, means for pivotally supporting the same comprising oppositely located shafts, one of the shafts having a plate attached thereto with a groove and projection connection to permit it to move or rock thereon, a pin on the plate, a second plate secured to the stove pipe and having sockets to receive the pin, means for operating the plate to withdraw the pin from the socket and to operate the 100 damper, said means including a flexible cord connected to the plate and passing through the periphery of a wheel connected to the 105 same shaft as the first mentioned plate.
